HANDLE FOR SPOONS, &c.

No. 20,078.

Patented Aug. 5, 1890.

Fig. 1.

Fig. 2.

UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 20,078, dated August 5, 1890.

Application filed July 7, 1890. Serial No. 368,007. Term of patent 14 years.

To all whom it may concern:

Be it known that I, AUSTIN F. JACKSON, residing at Taunton, in the county of Bristol and State of Massachusetts, have invented and produced a new and Original Design for Handles of Table-Spoons, Forks, &c., of which the following is a specification.

In the accompanying photographic illustrations, Figure 1 is a plan view of the face or front side of a spoon-handle, and Fig. 2 is a plan view of the back or reverse side of the same.

The design is intended for handles of ladles, knives, and analogous table-ware, as well as for spoons and forks, to which it is chiefly applied.

The most salient features of the design for the face side are the circular shape of the head or end *a* of the handle, the lateral contractions or notches *b* below the head, the contractions or notches *c*, and band *d*, located at about the middle of the length of the han-

dle, and the floral arabesque or other ornamentation *e*, applied to the border and also contiguous to the said band *d*. The back of the handle has the same general contour as the face, and also the band *d*, but the ornamentation *f*, contiguous to the latter, is simpler and less florid, as shown.

What I claim is—

1. In a design for a handle for spoons, &c., the face side of the handle, as shown in accompanying photograph.
2. In a design for a handle for spoons, &c., the reverse or back of the handle, as shown in accompanying photograph.
3. The design for the ornamentation of handles of spoons, &c., as shown in accompanying photographs.

AUSTIN F. JACKSON.
